(57) **CLAIM**

The ornamental design for a paint spray booth, as shown and described.

DESCRIPTION

FIG. 1 is a front, right and top perspective view of a paint spray booth, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the paint spray booth that form no part of the claimed design.
